FIG. 1

FIG. 3

FIG. 2

FIG. 4

FIG. 5

FIG. 6

FIG. 7

FIG. 1 is a perspective view of a combined children's playhouse and toy box showing my new design;

FIG. 2 is a right side view thereof;

FIG. 3 is a front view thereof;

FIG. 4 is a rear view thereof;

FIG. 5 is a top view thereof;

FIG. 6 is a left side view of a modified form thereof; and

FIG. 7 is a left side view of another modified form thereof.

The side opposite FIGS. 2, 6 and 7 are substantially the same as the side shown, and the front and rear view in FIGS. 6 and 7 are substantially similar in appearance to FIGS. 3 and 4.

I claim:

The ornamental design for a combined children's playhouse and toy box, as shown.
